UNITED STATES PATENT OFFICE

GEORGE W. PRENTICE, OF PROVIDENCE, RHODE ISLAND.

BUTTON-SETTING INSTRUMENT.

SPECIFICATION forming part of Letters Patent No. 294,744, dated March 4, 1884.

Application filed January 4, 1884. (No model.)

To all whom it may concern:

Be it known that I, GEO. W. PRENTICE, a citizen of the United States, residing at Providence, in the county of Providence and State 5 of Rhode Island, have invented certain new and useful Improvements in Dies for Setting-Instruments; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My invention relates to button-setting instruments; and it consists of a die having a peculiar form adapted to be wrought or formed in one of the jaws or members of the instrument, whereby one of the prongs of a two-pronged button-fastener is first deflected and bent parallel with and under the table or body 20 of the fastener, after which the other prong thereof is adapted, by means of the concave portion of said die, to be deflected beneath the former prong and at right angles therewith, and also clinched thereto, the fastener then 25 approximating an -shaped form.

My invention further consists in means for retaining the button, &c., in the instrument 30 during the operation of attachment, all as will be more fully hereinafter set forth.

In the accompanying sheet of drawings, Figure 1 represents a front view of a button-setting instrument provided with my improvement, showing a button and fastener in position for attachment to the fabric, a portion of each jaw being in section. Fig. 2 represents a top view of the same, with button and fastener removed. Fig. 3 represents a front view of the 35 instrument, showing the fastener clinched beneath the fabric, a portion of the upper jaw being removed. Fig. 4 represents a top view of the lower jaw, showing my improved clinching-dies formed therein. Fig. 5 represents, enlarged, a cross-section through *o o* of Fig. 4, showing the concave portion of my improved die. Fig. 6 represents a cross-section through *x x* of Fig. 3. Fig. 7 represents a button-fastener after being bent and clinched with my 40 improved die. Fig. 8 represents a plan view of the end of the lower jaw, showing the con-

cave portion of the clinching-die parallel with the jaw.

The object of my invention is to furnish means, consisting of dies of peculiar shape in 55 the jaw of a setting machine or instrument, whereby fasteners having two prongs may be inserted through the fabric and clinched thereunder, my invention being more particularly adapted to be used with that class of fasteners 60 represented in W. M. Hazel's patent, No. 259,656, of June 13, 1882.

The following is a description of my invention and its operation:

A in the drawings represents a button-setting instrument, consisting of the jaws or members *a b*, terminating, respectively, in handles *a' b'*. The upper surface of the lower jaw, *b*, has formed or secured therein at its end *b'* the longitudinal die-groove *z*, the outer end of said 70 die being slightly concave, the die also being of uniform depth throughout, and adapted to deflect and receive the long prong *n'* of the fastener *n*.

z' represents a concave and nearly semicircular-shaped die formed in said jaw *b'*, at right angles to and bisecting the said die *z*, the die *z'* being adapted to deflect and receive the short prong *n''* of said fastener.

That portion of the upper jaw, *a*, which retains the button and fastener is divided longitudinally into two parts, the front portion, *a''*, thereof being pivoted at *g*.

d d' represent recesses formed at the outer end of the jaw *a*, adapted to retain the button 85 *B* and its fastener *n* during the operation of attaching. To the inner arm, *a''*, of said lever *a''* is formed a wedge or cam shaped projection, *e*, adapted to engage with a similar and corresponding lug, *e*, of the lower jaw, as fully 90 shown.

The following is the operation of my invention: The end *a''* of the lever *a''* is depressed, thereby opening the jaw for the purpose of placing the button with its fastener *n* therein, 95 the spring *s* serving to assist in retaining them in position. The fabric or leather to which the button is to be attached is now placed in position beneath the depending fastener, when, by compressing the jaws of the instrument, the end *n'* of the long prong of said fastener is first inserted through the fabric, and, coming in con-

tact with the curved end of the die z , is deflect-
ed along said die and beyond the concave por-
tion z' thereof. At or about this stage of the
operation the end of the short prong n^2 of the
5 fastener is forced through the fabric and en-
gages with the outer edge of the concave die
 z' , when, finally, by now fully closing or con-
tracting the jaws, the latter prong is forced be-
neath and partially around the long prong, as
10 fully represented in Fig. 3, thus approximat-
ing an ∞ form. During the latter part of the
clinching operation the wedges $e e'$ of the jaws
engage with each other, thereby rigidly hold-
ing the button and fastener in position within
15 the upper jaw. By depressing the lever a^2 the
fabric, with its attached button, is released from
the instrument.

The fastener shown in Fig. 7 is adapted to
be clinched by means of my improved dies, or,
20 in fact, any fastener of that class having two
unequal prongs which are offset or not in line
with each other.

I do not claim, broadly, a button-fastener
clinched as represented, but ask protection for
25 the setting-instrument provided with the dies
adapted to clinch the prongs in the form and
manner shown and described.

Having thus described my invention, what
I claim as new, and desire to secure by Letters
30 Patent, is—

1. In a button-setting machine or instru-
ment provided with means for retaining a

button and fastener in position, the prong-de-
flecting device herein described, consisting of
the dies $z z'$, the latter having a concave form, 35
and arranged at right angles with and cross-
ing the die z , said dies being formed in a jaw
or member of said instrument, substantially as
shown, and for the purpose set forth.

2. The button-setting instrument A, herein 40
described, consisting of the jaws $a b$, the former
being provided with the pivoted supplemental
lever or jaw a^2 , and the jaw b being provided
with the clinching-dies $z z'$ and cam projec- 45
tion e , the whole combined and arranged sub-
stantially as shown, and for the purposes set
forth.

3. In a two-jaw button-setting instrument
provided with clinching-dies and wedge e , and
further provided with means for retaining a 50
button and pronged fastener in position, the
combination therewith of a supplemental le-
ver adapted to be pivoted to the button-hold-
ing jaw, and having a wedge or cam, e' , adapt-
ed to engage with the wedge e of its fellow 55
jaw, substantially as shown, and for the pur-
pose described.

In testimony whereof I have affixed my sig-
nature in presence of two witnesses.

GEORGE W. PRENTICE.

Witnesses:

CHARLES GREENE,
JAS. F. THAYER.
